D/16029

UNITED STATES PATENT OFFICE.

AUGUST SCHWARZSCHILD AND NELSON GREENFIELD, OF NEW YORK, N. Y.

DESIGN FOR CANDY OR CONFECTIONERY.

SPECIFICATION forming part of Design No. 16,029, dated April 7, 1885.

Application filed February 10, 1885. Term of patent 3½ years.

To all whom it may concern:

Be it known that we, AUGUST SCHWARZSCHILD and NELSON GREENFIELD, citizens of the United States, residing in the city, county, and State of New York, have invented and produced a new and original Design for Candy and Confectionery, of which the following is a specification, reference being had to the accompanying drawings, forming part thereof.

Figure 1 is a view of the top surface of our said new design, and Fig. 2 a plan view of the whole thereof.

This design we preferably use on chocolate creams or other confectionery formed of chocolate or combinations of chocolate.

The design consists in the shape and ornamentation of the chocolate or confectionery in the form of a truncated cone, the upper surface of which is surrounded with a raised rim or circumference, within which is represented

a star or star-like figure, which is the leading feature of the design.

In the drawings, A represents the annular outline, B the star on the top surface, and C the rim.

Having thus described our new design, what we claim is—

A design for candy or confectionery herein shown and described, consisting of the form of a truncated cone with the top surface in the ornamentation of a star or star-like figure surrounded with a raised rim or circumference.

In testimony whereof we have hereunto set our hands this 30th day of January, 1885.

AUGUST SCHWARZSCHILD.
NELSON GREENFIELD.

In presence of—

LOUIS W. FROST,
R. F. VAN. BOSKERCK.
